CLAIM

The ornamental design for a tree harvester, substantially as shown and described.

DESCRIPTION

FIG. 1 is a top, front and right side perspective view of a tree harvester showing our new design with the boom operatively positioned toward the rear of the vehicle; FIG. 2 is a rear and right side perspective view thereof with the boom operatively positioned in front of the vehicle;

FIG. 3 is a top, front and left side perspective view thereof with the boom operatively positioned in front of the vehicle and with the boom gripping claws in closed condition;

FIG. 4 is a front perspective view thereof with the boom operatively positioned toward the rear of the vehicle; and

FIG. 5 is a top perspective view thereof with the boom operatively positioned in front of the vehicle and with the boom gripping claws in open condition.

FIG. 1.

FIG. 2.

FIG. 3.

FIG. 5.

FIG. 4.
